UNITED STATES PATENT OFFICE.

HOMER E. FROST, OF CLEVELAND, OHIO, ASSIGNOR TO THE ELECTRIC CONTROLLER AND MANUFACTURING COMPANY, OF CLEVELAND, OHIO, A CORPORATION OF OHIO.

ELECTRIC-MOTOR CONTROLLER.

1,103,954.

Specification of Letters Patent. Patented July 21, 1914.

Application filed September 13, 1913. Serial No. 789,654.

To all whom it may concern:

Be it known that I, HOMER E. FROST, a citizen of the United States, residing at Cleveland, in the county of Cuyahoga and

5 State of Ohio, have invented new and useful Improvements in Electric-Motor Controllers, of which the following is a specification.

10 My invention relates to an electric motor controller in which the motor circuit is controlled at the contacts of a manually-operated switch and at the contacts of a series of magnetically-operated switches.

15 More particularly, it relates to such a controller in which the operating windings of the switches are arranged to be connected in the motor circuit.

20 One of the objects of my invention is to enable the operator to maintain at will the maximum resistance in the motor circuit.

A further object is to prevent the closure of the first magnetically-operated switch until the first section of the starting resistance has been cut out at the contacts of the 25 operator's switch.

Other objects and advantages of my invention will be readily understood as hereinafter described.

The accompanying drawing is a diagrammatic representation of an electric controller embodying my invention.

Referring to the drawing, the switch for controlling the motor is indicated at M, which has stationary and movable contacts 35 including connections for reversing the motor.

The motor to be controlled is indicated with the armature A and the series field F.

The starting resistances are shown at R, 40 R', R², and R³.

The magnetically-operated switches for controlling the resistance are indicated at switches S', S², and S³, these switches having operating windings C', C², and C³ arranged to be connected in the motor circuit. I prefer to use for these switches the type of switch disclosed in Eastwood's Patent, No. 1,040,292 which has the peculiar characteristic of remaining in the open position 45 when the current in its operating winding is above a predetermined value, and operates to close its contacts when the current is reduced.

The switch S' is provided with a winding 50 B connected across the resistance R and,

therefore, is energized by the current flowing through the resistance R. The winding B is wound so as to oppose the magnetism produced by the winding C' and thereby prevents the operation of the switch S' as long as the current flows through the resistance R. The winding C' is connected in series with the resistance R so that as the current rises and falls in resistance R it will vary to the same extent in both of the 65 windings C' and B, thus preventing the operation of the switch S' as long as the resistance R is in circuit.

When the operator moves the switch M to position 1, the motor circuit is as follows: 70 From the positive through the field winding F, the contact finger 8, the controller contacts to the contact finger 7, the motor armature A to the contact finger 9, the controller contacts to the contact finger 10, the resistances R and R', the winding C', and the resistances R² and R³ to the negative. The winding B is energized to oppose the winding C' in proportion to the current flowing through the resistance R. The 75 switch S' will, therefore, remain open as long as the operator's switch remains in position 1. The maximum resistance will be retained in the motor circuit and the motor will operate at its slowest speed.

When the operator moves the switch M to position 2, the resistance R is cut out and the winding B of the switch S' is deenergized, the resistance R being short-circuited by the contact fingers 9 and 12 through the 80 contacts of the controller. If the current in the motor circuit exceeds a certain value, the switch S' will remain open; and when it is diminished below this value, the switch S' closes but does not cut out any of the starting 85 resistance. When the operator moves the switch M to position 3 the lower connection of the winding C² of the switch S² is connected through the contact finger 13 to the contact fingers 9 and 10 and the motor circuit then goes from the contact finger 13 through the winding C², the contacts of the switch S', the winding C', and the resistances R² and R³ to the negative. The resistance R' is cut out causing the motor to 100 further increase its speed. If the motor current exceeds the value at which the switch S² is adjusted to operate, it will remain open until the motor current is diminished, whereupon the switch S² closes 105

55 110

- Its contacts, cuts out the resistance R^2 , energizes the winding C^3 , and deenergizes the winding C' . The switch S' thereupon drops open and the switch S^3 remains open, due to the increased current, until it is diminished to the value to which the switch S^3 is adjusted to operate, whereupon the switch S^3 closes its contacts and cuts out the resistance R^3 . All of the starting resistance is now removed from the motor circuit, there remaining in the circuit only the windings and the contacts of the switches S^2 and S^3 . The motor will accordingly operate at its normal speed.
- 15 When the operator's switch is moved back to position 2, the circuit through the windings and the contacts of the switches S^2 and S^3 will be opened and the resistances R' , R^2 , and R^3 will be inserted in the motor circuit causing the motor to decrease its speed. The switch S' will close its contacts since its winding C' is included in the motor circuit at this time, but the switch S' cannot cause any of the starting resistance to be short-circuited unless the operator's switch is again moved to position 3.
- 20 When the operator's switch is moved to position 1, the resistance R will be inserted in the motor circuit causing a further reduction in the speed of the motor and the winding B will be energized causing the switch S' to open. To stop the motor the operator's switch is moved to the central position as shown in the drawings, thereby opening the motor circuit.
- 25 When all the resistance is in the motor circuit, the switch S' remains open regardless of the value of current flowing in the motor circuit. When the resistance R is short-circuited by the movement of the operator's switch, the switch S' will remain open only as long as the motor current exceeds a predetermined value. A further removal of the starting resistance cannot take place 30 until the operator's switch has been moved to position 3 whereupon the switches S^2 and S^3 proceed to automatically cut out the remainder of the starting resistance. Connections are so made with the contacts and 35 windings of the switches S' and S^2 that, when the windings are deenergized, practically no current flows through the switch contacts. Therefore, the switches open at a time when little or no current flows through 40 their contacts, thus preventing any serious arcing at the switch contacts. This is an advantage, because it is not necessary to provide blow-out magnets and the necessary details to extinguish arcs at the contacts of 45 the magnetically-operated switches.
- 50 When the operator's switch M is moved to positions 4, 5 and 6, the operation will be the same as that described for the positions 1, 2 and 3 except that the current through 55 the motor armature will be reversed causing

the motor to run in the opposite direction. In reversing the motor all the resistance can be retained in the motor circuit, if the controller is moved to position 1 or 4. It will be automatically removed by the closure of the switches S' , S^2 , and S^3 in accordance with the current flowing through the motor circuit when the controller is moved to position 3 or 6.

70 It will be obvious to those skilled in the art that numerous changes can be made in the apparatus without departing from the spirit of my invention.

I claim—

1. In a current-varying controller, a controlled circuit, resistance therefor, a series of switches for controlling the resistances, operating windings therefor energized by current in the controlled circuit, an operator's switch comprising contacts for connecting the resistances and the winding of the first switch in the controlled circuit, and means for preventing the operation of the said switch when all the resistances are in circuit.

80 2. In a current-varying controller, a controlled circuit, resistances for the circuit, a series of switches for controlling the resistances, operating windings therefor energized by current in the controlled circuit, 85 means connected to the resistance for preventing the operation of the first switch of the series and an operator's switch comprising contacts for connecting the resistances and the operating winding of the first switch in the controlled circuit, and for cutting out a portion of the resistance, thereby deenergizing the said preventing means.

90 3. In a current-varying controller, a controlled circuit, resistances therefor, a series of switches for controlling the resistances, operating windings therefor energized by current in the controlled circuit, a preventive winding for the first switch of the series, and an operator's switch comprising contacts for connecting the resistance and the operating winding of the first switch of the series in the controlled circuit, and for connecting the winding of the second switch in the controlled circuit.

100 4. In a motor-control system, an electric motor, a circuit therefor, resistance in the circuit, a series of switches therefor, operating windings for the switches energized by current through the motor, means for connecting the resistance and the winding of the first switch in the motor circuit, means for preventing the closure of the first switch when all the resistance is in circuit, and means for cutting out at will a portion of the resistance, thereby permitting the said first switch to close.

110 5. In a motor-control system, an electric motor, a circuit therefor, resistance in the circuit, operating windings therefor energ- 120

gized by current through the motor, means for connecting the resistance and the winding of the first switch of the series in the motor circuit, means for preventing the closure of the first switch when all of the resistance is in the circuit, means for cutting out at will a portion of the resistance thereby permitting the said first switch to close, and means for connecting the operating winding of the second switch in the motor circuit at the will of the operator.

6. In a current-varying controller, a controlled circuit, resistances therefor, a series of switches for controlling the resistances, 15 operating windings therefor energized by current in the controlled circuit, an operator's switch comprising contacts for connecting the resistances and the winding of the first switch in the controlled circuit, 20 and a winding on the first switch energized

by current in a portion of the resistance for preventing the closure of the said switch when all the resistances are in circuit.

7. In a current-varying controller, a controlled circuit, resistances therefor, a series 25 of switches for controlling the resistances, operating windings therefor energized by current in the controlled circuit, an operator's switch comprising contacts for connecting the resistances and winding of the 30 first switch of the series in the controlled circuit, and a winding connected to a portion of the resistance for neutralizing the operating winding of the said first switch.

Signed at Cleveland, Ohio, this 11th day 35 of September, 1913.
